UNITED STATES PATENT OFFICE

157,537

CASING FOR A THERMOSTAT OR THE LIKE

Joe Roos, Jr., St. Louis, Mo., assignor to Missouri Automatic Control Corporation, St. Louis, Mo., a corporation of Missouri

Application March 25, 1947, Serial No. 137,856

Term of patent 14 years

(Cl. D52—7)

To all whom it may concern:

Be it known that the undersigned, Joe Roos, Jr., a citizen of the United States, residing in the city of St. Louis, State of Missouri, has invented a new, original, and ornamental Design for a Casing for a Thermostat or the like, of which the following is a specification, reference being had to the accompanying drawing, forming a part thereof, in which:

Fig. 1 is a plan view of a casing for a thermostat or the like, showing my new design;

Fig. 2 is a front elevation thereof;

Fig. 3 is a bottom view thereof; and

Fig. 4 is a side elevation thereof.

The characteristic features of my design reside in the portion shown in solid lines.

I claim:

The ornamental design for a casing for a thermostat or the like, substantially as shown and described.

JOE ROOS, JR.
